UNITED STATES PATENT OFFICE.

JOHN W. DARLEY, JR., OF BALTIMORE, MARYLAND, ASSIGNOR TO WILLIAM KNABE & COMPANY MANUFACTURING COMPANY OF BALTIMORE CITY, OF BALTIMORE, MARYLAND, A CORPORATION OF MARYLAND.

SELF-PLAYING PIANO.

No. 839,559.

Specification of Letters Patent.

Patented Dec. 25, 1906.

Application filed January 13, 1906. Serial No. 295,988.

To all whom it may concern:

Be it known that I, JOHN W. DARLEY, JR., a citizen of the United States, residing at Baltimore city, State of Maryland, have invented certain new and useful Improvements in Self-Playing Pianos; and I do hereby declare the following to be a full, clear, and exact description of the invention, such as will enable others skilled in the art to which it appertains to make and use the same.

My invention relates to improvements in self-playing pianos of the type shown in my former patent, No. 813,355, dated February 20, 1906; and the object of my invention is to provide means whereby after the key-slip has been folded down to lock the keys and the pedal-board folded down to bring the pneumatic apparatus into action said keys may be unlocked and operated by the player without the necessity of folding back the pedal-board.

With these objects in view my invention consists in the construction and combinations of parts, as hereinafter described and claimed.

In the accompanying drawings, Figure 1 is a side view of a piano with one of the ends removed. Fig. 2 is a broken front view with a part of the top casing removed. Fig. 3 is a side view, partly in elevation, showing the mechanism for locking the keys out of operation. Fig. 4 is a similar view showing the locking means holding the keys locked, and Fig. 5 is a detail view showing a part of the pedal attachment for unlocking the keys after the pedal-board has been folded down.

a represents one of the ordinary pivoted keys, and *b* represents a bar extending across the piano and adapted when lowered to lock said keys against movement, resting upon strips of felt *c* on said keys. The bar *b* is supported in brackets *d*, one of which is pivoted, as shown at *e* in Fig. 1, to each side of the piano. Each of the brackets *d* is slotted, as shown at *f*, and a headed screw *g* passes through said slot into the bar *b*, thereby making the latter adjustable upon said brackets. These brackets *d* are of considerable size and weight, and unless positively prevented they will assume the position shown in Fig. 4, bringing the bar *b* into con-

tact with the keys *a* and locking them by gravity.

h represents a key-slip pivoted on the front frame of the piano and arranged to fold outwardly, as shown in Fig. 4. To this key-slip *h* is attached a lever *i*, which is bent downwardly, as shown at *j*, and provided with a horizontal pin *k*. This pin *k* when the key-slip is folded down, as shown in Fig. 4, is brought into contact with the projecting end *m* of a rotating locking-rod *n*, moving it against the tension of the spring *o*. The lower end of the rod *n* is provided with a hook *p*, which engages a slot *q* in the upper part of the pedal-board *r*, which is adapted to fold down, so as to bring the pneumatic attachment into operation.

It is obvious from the description and the construction shown in Figs. 3 and 4 that the folding down of the key-slip will move the lever *i* forward, whereupon the pin *k* will strike the end *m* of the lever *n* and unlock the pedal-board, whereby the latter will fold by the pressure of the spring *o* into the upper position. (Shown in dotted lines in Fig. 1.)

From the upper position (shown in dotted lines in Fig. 1) the pedal-board may be folded down into the lower position, (shown in dotted lines in said figure,) in which position the piano may be operated as a self-playing instrument.

s represents a portion of the folding pedal-board pivoted to the frame, as shown at *t*. Pivoted to the bottom board *s* is a push-rod *u*, which extends up between the keys and the upper end of which contacts with a block *v*, fastened to the center of the bar *b*. When the pedal-board is folded up, as shown in Fig. 3, the rod *u* holds the locking means away from the keys, as shown in Fig. 3; but when the pedal-board is folded down, as shown in Fig. 4, the rod *u* is drawn down, whereupon the bar *b* falls down and across the keys, being carried down by the heavy brackets *d*.

To provide means whereby the player may operate the keys without the necessity of folding up the keyboard, I have devised the following: To the soft pedal *w*, which is pivoted, as shown at *x*, to the lower part of the frame, is fastened an upwardly-extending bolt or rod *y*, which is adjustably attached,

by means of nuts, such as 1, to one end of a lever 2, which is pivoted, as shown at 3, in brackets 4, extending upwardly from the bottom of the piano.

- 5 To the other end of the lever 2 is pivotally attached, as shown at 5, a push-rod 6, the upper end of which operates the soft-pedal attachment 7; but which is separated therefrom by a space, as shown in Fig. 2. The 10 push-rod 6 is provided with a slot 8, through which passes a pin 9 on one of the brackets d, the result being that when the push-rod 6 is in its lowest position, as shown in Fig. 4, the bar b will be permitted to fall into the 15 position shown in the same figure; but when the push-rod 6 is pushed up, as by the downward movement of the soft-pedal, the bar b will be lifted and the keys a released, so that they may be operated by the player even 20 when the key-slip h is folded down, as shown in Fig. 4. A spring 10 normally holds the lever 2 in the position shown in Fig. 2. Sufficient lost motion is provided between the end of the rod 6 and the soft-pedal attachment 7, so that the first motion of the pedal w merely lifts the bar b and does not operate the soft-pedal attachment, which latter can be operated, however, by a further depression of the pedal w.
- 25 30 The other parts of the piano are substantially the same as those set forth in my prior patent above referred to.

Having thus described my invention, what I claim as new, and desire to secure by Letters Patent, is—

35 1. In a self-playing piano, the combination of a pedal-board, keys, a locking means for said keys, a device operated by said pedal-board for operating said locking means, and 40 separate means for disengaging said locking means without the movement of the pedal-board, substantially as described.

2. In a self-playing piano, the combination of a pedal-board, keys, a locking-bar for 45 said keys, a means for holding said locking-bar out of engagement with said keys and permitting said locking-bar to engage with said keys by the operation of the pedal-board, and separate means for moving said locking 50 means out of engagement with said keys, substantially as described.

3. In a self-playing piano, the combination of a pedal-board, keys, a gravity-operated locking-bar for said keys, a means for holding 55 said locking-bar out of engagement with said keys and for permitting said locking-bar to engage with said keys by the operation of the pedal-board, and separate means for moving said locking-bar out of engagement with said 60 keys without operating the pedal-board, substantially as described.

4. In a self-playing piano, the combination of keys, a locking-bar for said keys, means for holding said locking-bar out of engagement with said keys, a pedal-board connect-

ed to said holding means, means for locking and unlocking said pedal-board, and separate mechanism for moving said locking-bar out of engagement with said keys without operating said pedal-board, substantially as described. 70

5. In a self-playing piano, the combination of keys, a gravity-operated locking-bar for said keys, a pivoted pedal-board, means operated by said pedal-board for holding said 75 bar out of engagement with said keys, means for locking and unlocking said pedal-board, including a pivoted key-slip, and connections between said key-slip and said pedal-board, and separate means for moving the locking 80 means out of engagement with the keys without the movement of the pedal-board, substantially as described.

6. In a self-playing piano, the combination of keys, a locking-bar for said keys, a pivoted 85 pedal-board, a push-rod connected to said pedal-board, and holding said locking-bar out of contact with said keys when the pedal-board is folded up, means for locking said pedal-board, including a hooked rod, a pivoted key-slip, and a rod operated by said key-slip for moving said rod, and separate means for moving said locking-bar out of contact with said keys without the movement of the 90 pedal-board, substantially as described. 95

7. In a self-playing piano, the combination of a pivoted pedal-board provided with a catch, a rod provided with a hooked end, a spring bearing against said rod, a pivoted key-slip, and a bent rod attached thereto and carrying a pin, said pin being adapted to strike said hooked rod and unlock said pedal-board when said key-slip is folded down, 100 keys, a locking-bar for said keys, and separate means for moving said locking-bar out of contact with said keys after it has been brought into contact therewith by the movement of the pedal-board, substantially as described. 105

8. In a self-playing piano, the combination 110 of keys, means for locking the same, a pivoted pedal-board, means for locking said pedal-board in an upright position, means whereby the releasing of said locking means will lock said keys, and separate means for moving 115 the locking means out of contact with said keys without the movement of the pedal-board, said separate means consisting of a pedal, a lever connected thereto, a push-rod operated by said lever and provided with a slot, and a pin carried by the locking means for the keys, said pin engaging said slot, substantially as described. 120

In testimony whereof I affix my signature in presence of two witnesses.
